CLAIM

The ornamental design for an integrated sensor assembly, as shown and described.

DESCRIPTION

This application is related to U.S. design application Ser. No. 29/729,714, filed concurrently herewith, entitled Integrated Sensor Assembly, the entire disclosure of which is incorporated by reference.

FIG. 1 is a front perspective view of an integrated sensor assembly according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines illustrate portions of the integrated sensor assembly that form no part of the claimed design.
